CLAIM

The ornamental design for a pacifier holder, as shown and described.

DESCRIPTION

1. Pacifier holder

1.1 : top plan view of the pacifier holder, shown closed in a first configuration.

1.2 : bottom plan view, thereof.

1.3 : front elevation view, thereof.

1.4 : right side elevation view, thereof.

1.5 : top, front, right perspective view, thereof.

1.6 : sectional-elevation view, shown in the first configuration.

1.7 : sectional-perspective view, shown in the first configuration.

1.8 : top, left perspective view, shown open in a second configuration with interior element inverted.

1.9 : right side elevation view, thereof.

1.10 : top plan view, shown in the second configuration, with interior element removed for clarity of disclosure.

1.11 : bottom plan view, thereof.

1.12 : top plan view, shown in the second configuration with interior element upright.

1.13 : top, front, right perspective view, thereof.

1.14 : top, front, right perspective view, shown in the second configuration with interior element inverted.

1.15 : top, front, right perspective view of the pacifier holder, shown exploded for clarity of disclosure.
